MINING OF SULPHUR.

Application filed March 15, 1924. Serial No. 699,448.

This invention relates to improvements in the mining of sulphur, and includes an improved method for the mining of sulphur by underground fusion, as well as an improved system or apparatus therefor.

In the mining of sulphur by underground fusion, in accordance with the so-called Frasch process, a hole or well is drilled through the overlying strata to the bottom of the sulphur formation, which hole is usually cased with an eight-inch or ten-inch pipe, and then, through a system of concentric pipes appropriately arranged within this casing, superheated water is pumped down to the foot of the hole or well where it is discharged into the sulphur formation and melts the sulphur. The melted and liquid sulphur enters one of the concentric pipes, usually through a strainer, and is raised to the surface of the ground, generally by means of an air lift. The well continues to operate and produce sulphur until the sulphur-bearing formation is locally exhausted, or until the piping equipment is broken by subsidence of the ground due to the extraction of the sulphur content.

The sulphur formation is usually found in the form of so-called domes, at depths varying from around 500 to 1500 feet below the surface of the ground. These sulphur domes are usually overlaid by a porous cap rock formation of limestone which in turn is overlaid by gumbo, quicksand and clay. Beneath the sulphur formation is usually found a layer of gypsum or anhydrite, and layers or domes of salt.

The sulphur formation itself usually contains the sulphur distributed in a porous rock formation which also contains a large amount of water forming what may be considered an underground lake of brine or salt water containing, for example, about 4800 grains per gallon of solid in solution, mainly sodium choride, and in addition hydrogen sulphide and other soluble sulphides. Such water is corrosive and destructive to the well-pipes and other metal with which it comes in contact.

In the so-called Frasch system of mining sulphur by underground fusion, hot water is the vehicle commonly used for conveying and transmitting heat to the sulphur. Inasmuch as sulphur melts at a temperature around 240° F., which is above the boiling

point of water at atmospheric pressure, the 55 heating water is highly superheated and is pumped into the mine under a high pressure. The temperature to which the water can be superheated is however limited by the danger of overheating the sulphur in which 60 case it becomes viscous. Accordingly, the water is heated to a temperature which avoids overheating of the sulphur but which is sufficiently above the melting point of the sulphur to bring about effective melting 65 thereof as the highly heated water comes in contact with the underground sulphur. The water may thus be heated under pressure to about 320° F. and pumped into the sulphur deposit, this water replacing the 70 sulphur removed by the well together with water already contained in the deposit, which may be withdrawn by means of bleed-wells, situated at suitable points in the deposit. The bleed wells are usually located 75 so as to withdraw the cold brine or salt water from the lower part of the sulphur formation.

The sulphur dome may underlie a considerable surface area of ground. The dome 80 may, for example, be as much as a mile in diameter; and the underground lake forming a part of the deposit or adjacent thereto may contain billions of gallons of underground water or brine.

In the mining of such a sulphur deposit, one or several wells are usually drilled and operated at one part of the deposit until the sulphur bearing formation is exhausted locally and then other wells are drilled at another part of the deposit, and the deposit is progressively worked in this way until exhausted. The operation of a sulphur mine in this way is an operation of large magnitude. The amount of highly heated water 90 which it is necessary to pump into the deposit in a single day may amount to several million gallons in commercial operations.

The pumping of a large amount of super-heated water into the deposit results in the gradual accumulation of a progressively increased amount of hot water in the deposit. The specific gravity of the original deposit temperature for example about 108° F., while temperature for example about 108° F., while the specific gravity of the clean hot water pumped into the mine is in the neighborhood of 0.91. Owing to this difference in

specific gravity, the hot water rises or tends to rise to the top of the dome, displacing the cold deposit water downward, and, while there is some diffusion and mixing, in a general way the water at the top of the dome becomes cleaner and hotter with only a small amount of solids in solution, while the water in the lower part of the deposit contains its original content of dissolved solids until displaced by the cleaner water from above.

The rapid filling of the dome, or the upper portion of the dome, with hot water in this way, may be objectionable, as it may result in the melting of a large quantity of sulphur which may be so situated that it will not drain through the wells which are being operated, on account of the large area of the dome, and this sulphur will become discolored by being held for a considerable time in a molten condition, before it can be extracted.

Furthermore, the continued supply of a large amount of highly heated water to the mine forms one of the major expenses of the operation, this water being commonly obtained from a source several miles distant from the mine at a temperature around, for example, 68° F., and being heated to a temperature around 324° F. before it is pumped into the mine. Of the total heat supplied to the water, only a small part is available for melting the sulphur. Thus, in heating water from 68° F. to 324° F., 256 B. t. u.'s are supplied by the combustion of fuel to each pound of water which is pumped into the deposit. Since sulphur melts at around 240° F., the only effective heat supplied to the water is that between the maximum temperature of the water and the melting point of sulphur, for example, around 85 B. t. u.'s of the total of 256 B. t. u.'s supplied to the water.

The present invention provides an improved method and system of mining sulphur whereby important economy of operation is obtained, and whereby the mining of the dome as a whole can be better regulated and controlled, and whereby a greatly increased fuel efficiency, and decreased fuel consumption can be effected.

The present invention is of particular advantage in the mining of sulphur from deposits which have been operated for considerable time until there has accumulated a large amount of hot water in the upper portion of the dome or formation from which the sulphur has been exhausted. If fresh hot water were continually pumped into the deposit and permitted to accumulate therein, the hot water collecting in the top of the dome would gradually displace the cold deposit water downward until eventually, with suitably located bleed wells, all of the original deposit water would be removed and replaced by fresh water which in

turn will be replaced by hotter fresh water until the whole deposit would become heated, and heat would be wasted by further bleeding. This rapid accumulation of hot water, and rapid displacement of the cold brine water downward, would serve to heat the lower part of the deposit, including those parts remote from the point where the sulphur is being mined; and although the hot water from above is cooled as it works downward by heating the deposit, and although there would be a descending scale of temperature as lower levels in the deposit were reached, yet the heating of the deposit would not be regulated in a manner best adapted for the satisfactory mining of the sulphur.

According to the present invention, this rapid filling of the deposit area with hot water is avoided, and the operation of the deposit is regulated and controlled in such a way that the heating is most effectively applied where it is desired.

In the practice of the present invention, a part of the hot water from the top of the deposit, after a large accumulation of hot water has occurred, is withdrawn and re-heated and utilized over again by introducing it into the sulphur wells; and this withdrawal and reutilization of the hot water from the mine is regulated and controlled so as to give a regulation and control of the mining operation.

The present invention includes an improved method and system for withdrawing hot water from the mine and for reheating and reutilizing this water. The invention also includes improved methods for heating the water so as to enable it to be used in a regulated and advantageous way in the carrying out of further mining operations.

In the carrying out of the present invention, I withdraw hot water from the top or upper part of the dome or deposit where it accumulates in the exhausted area and in the porous cap rock, and I maintain this water at a temperature above the boiling point of water at atmospheric pressure by keeping the water under pressure while it is being withdrawn, and I reheat this water while still maintaining it under pressure and again force it down into the deposit through the well where the active mining operation is going on. This hot water in the top of the deposit forms a heat reservoir where the heat is not utilized to melt sulphur and where only a heat loss is involved in the usual mining operation. Instead of obtaining only a low heat efficiency from the hot water pumped down into the ground by permitting it to accumulate and increase in amount in the deposit, I withdraw a part of this water from the part of the deposit where it is at a high temperature and preferably where it is relatively hottest and I thus avoid the rapid accumulation of hot water which would take

place if this water were not so withdrawn, and if only cooler or cold water from the lower part of the deposit were withdrawn through bleed wells.

Furthermore, I reintroduce this water after the addition of sufficient heat to give the maximum heating efficiency, (i. e. the necessary heat units to raise the temperature of the water to about 320° F.), in the localized well zone or zones where its heat is utilized, and I thus obtain a regulated flow, so to speak, of hot water from the well zone to the top of the deposit from which it is again withdrawn for further reheating and reintroduction into the deposit at the well zone. I do not, however, in ordinary operations, withdraw an amount of hot water equal to that introduced into the mine, but I introduce a somewhat larger amount of hot water than the amount which I withdraw, so that there is a progressive but gradual increase in the amount of hot water accumulating in the deposit. In conjunction with this introduction of hot water and withdrawal of hot water, I also withdraw cooler water or cold water through bleed wells from the lower levels of the deposit. This is the operation which the invention involves during the period when there still remains cold mine water requiring to be removed.

When eventually the original mine water is substantially all withdrawn, and replaced by hot water, so that further loss of water through bleed wells would involve an important heat loss, I may withdraw an amount of hot water from the deposit nearly equal to the amount reintroduced. By regulating the amount of hot water withdrawn, in relation to the amount of hot water introduced, I am enabled to operate the deposit as a whole, or localize parts of the deposit, in a particularly advantageous way; and I am enabled to change the operation so that, at the beginning of the operation, hot water may be introduced without any withdrawal of hot water, until a substantial accumulation has occurred; and I may then withdraw a regulated amount of hot water, less than the amount reintroduced, so as to obtain a gradual and regulated increase in the amount of hot water in the deposit; until finally I may withdraw hot water at a rate approximating that at which the hot water is reintroduced.

In the carrying out of the process of the invention, the hot underground water, which is at a high temperature and pressure, e. g. at a temperature between 200° F. and 300° F. or more and at a pressure of greater than atmosphere is withdrawn and kept under pressure while it is being withdrawn, by means of a pump, an injector or other suitable means, and this water so withdrawn under pressure and with its temperature maintained is used as a vehicle or conveyor

for additional heat units and is then again introduced into the deposit. One advantageous method of maintaining this water under pressure, and of preventing it from being cooled to 212° F. by reduction of its pressure to atmospheric, is to introduce a centrifugal pump into the line through which the water is withdrawn, and at a sufficient level to receive the water while still under a sufficient pressure to prevent its partial vaporization.

When the hot mine water is thus withdrawn, it is reheated, or reheated and subjected to purification, for example, by the use of lime, metallic iron, copper, charcoal, fuller's earth or other suitable material, before it is reintroduced. Iron or copper, for example, will serve to deposit soluble sulphides and prevent corrosion of the well pipe; lime will serve to prevent corrosion by chlorides. Fuller's earth, charcoal, or other suitable material will serve to remove oil, etc.

The present invention provides various novel methods of reheating this mine water for reuse, as well as advantageous methods of treating the mine water for its purification for reuse.

One advantageous method of reheating the mine water is to feed into it sufficient live steam under suitable pressure to raise its temperature to around 320° F. so that it can be returned to the sulphur-producing wells for further use in a mining operation. This method is particularly advantageous during the later stages of the mining of the sulphur in the dome, after all or practically all of the original salt water has been removed, and after the dome is filled for the most part with relatively pure water. Ordinarily, however, the water withdrawn may not be sufficiently pure to permit of its reheating and reintroduction in this way; and, in such cases, the present invention provides for the treatment of this water so as to permit it to be reused. Where the mine water contains scale forming material, it is subjected to a treatment by filtering or settling in mud drums either before reheating, or more advantageously after reheating, or both before and after reheating. After the dome is fairly well filled with hot fresh water, the water withdrawn will require relatively less purification, but it may nevertheless be advantageously purified in the manner described, where it is heated by the introduction of live steam and without the admixture of any considerable amount of fresh water therewith.

According to another method of the present invention, the hot water withdrawn from the mine under pressure is admixed with fresh hot water of a much higher temperature so that the admixed mine water and fresh water will have the desired temperature for reintroduction into the deposit.

Fresh water can thus be heated at the boiler plant to a temperature as far above 320° F. as possible, for example, to a temperature of about 364° F., and then mixed with the water drawn from the mine in such proportions that the resulting mixture will have a temperature of around 320° F., at which temperature it can be returned to sulphur-producing wells.

10 This method of reheating has the advantage that the fresh water used dilutes the impurities in the hot water from the mine, and prevents to a large extent the formation of scale which might interfere with the operations. Thus where the water withdrawn from the mine contains gypsum, the heating of this mine water without dilution would tend to cause precipitation of the gypsum, or of part of the gypsum, but the dilution of 15 the mine water with fresh water tends to neutralize or overcome this precipitation and to hold the gypsum in solution even at the higher temperature of the admixed fresh and mine water. This admixture of fresh 20 hot water with the mine water has the further advantage that it renders possible the continuation of the filling of the dome with fresh water at a rate regulated by the amount of fresh water so admixed, and introduced.

30 Instead of reheating the mine water by steam alone, or by admixture with highly heated fresh water, a combination of these two methods may advantageously be employed so as to obtain the advantages or certain of the advantages resulting from the use of fresh mine water and also an increased flexibility of operation, whereby maximum economy is made possible.

40 The invention also includes improvements in the treatment of the hot water withdrawn from the mine for the separation of oil therefrom. The oil which may be contained in small amounts in the hot water in the mine tends to separate from the water accumulating in the top of the dome and to accumulate in the upper layers at or above the top of the hot water. The water withdrawn from the top of the deposit may thus contain appreciable amounts of oil admixed therewith. This amount will ordinarily be larger at the beginning of the withdrawal of the water, because of the accumulation of oil which has been taking place, and the amount of oil in the water withdrawn may, after the operation has been continued for sometime, become so small as not to cause trouble. Where however there is an appreciable amount of oil in the water, the water 50 is treated in the process of the present invention to separate the oil therefrom so that the oil will not be again introduced to contaminate the sulphur. In order to remove 55 this oil, where it is present in appreciable amounts in the mine water withdrawn, the

60 apparatus is provided with a trap or with a baffled receiver through which the water flows slowly, or with a filter such as is used for condenser water in marine or large engine practice, and the oil is thus separated 70 from the water before its reuse in further mining operation.

65 Trouble from oil can also be largely reduced or overcome by extending the pipes through which the water is withdrawn to a 75 point somewhat below the top of the water layer and well down into the cap rock so as to provide a place above the lower end of the pipe where the oil can collect without being withdrawn with the water. Oil 80 accumulating in this way can be bled through the casing if it accumulates in sufficient quantity, as where the water has remained more or less at rest for a considerable period of time and segregation of the oil toward the 85 top has been permitted to take place over a considerable period before the withdrawal of hot water begins.

90 The invention will be further described in connection with the accompanying drawing which illustrates in a conventional and graphic manner a section of a mine and of apparatus embodying the invention and adapted for the practice of the process of the invention. The showing is largely conventional, and various parts are magnified, and the horizontal dimensions of the pipe and of various parts are magnified for convenience of illustration.

95 In such a mine as represented in the accompanying drawing, the sulphur deposit is usually overlaid by a cap rock formation of limestone, above which is gumbo, quicksand and clay. Below the sulphur deposit there are usually bodies of gypsum and salt. In the drawing, there is represented a region marked "Hot water zone" from which it is assumed the sulphur has been melted, and which is assumed to be full of hot water 100 accumulated from the mining operation. The hot water will also extend upwardly into the porous cap rock. It will be apparent that as the sulphur is melted and withdrawn, the space originally occupied by the sulphur must be filled either by the subsidence of the earth above or by the hot water 105 pumped into the mine. It will also be understood, as above explained, that the hot water which is pumped into the mine where the active mining operation is going on, is lighter than the cold salt water originally contained in the mine, so that the fresh hot water tends to rise and to accumulate in the 110 upper levels of the dome.

115 In the drawing, one of a series of active sulphur wells is indicated at 1, this well being made up as usual of a series of concentric pipes within a casing tube. For convenience of illustration, the entire series 120 of pipes is omitted and only two concentric 125

pipes are shown, the inner pipe 3 being intended to illustrate graphically the pipe through which the molten sulphur is pumped from the mine and which extends 5 to the bottom of the deposit, and the outer casing 2 illustrating the outer pipe within which the hot water is pumped down into the mine.

Connected with the well 1 is a pipe 4 10 which leads the high pressure superheated water from the power plant to the mine. In starting operations of the mine, all of the hot water pumped down into the mine is supplied in this way. The water thus supplied 15 is heated from e. g. 68° F. to around 320° or 324° F. and is supplied at the latter temperature to the mining operation.

A bleed well 5 is shown as located at a 20 distance from the active sulphur mine and as leading from a lower level of the deposit from which the colder salt water will be withdrawn in regulated amount. During the early stages of the mining operation, the bleed wells may discharge salt water at a 25 rate the same as or approximately the same as the rate of introduction of fresh hot water into the mine.

A well 6 is shown as located so as to withdraw water from the top of the dome. This 30 well extends down into the porous cap rock and at its upper end is enlarged so as to accommodate a suitable pump, shown as a centrifugal pump 8 driven by a motor 9 and having an extension 10 extending down 35 into the hot water zone and which may terminate in a perforated end 11 through which the hot water is admitted into the pipe 10 and thence into the centrifugal pump 8. The well pump 8 may be of any suitable 40 construction for keeping the water under pressure so that no expansion or freeing of steam can take place near or at the surface of the ground. A heavy duty centrifugal pump such as a multi-stage centrifugal pump can be used. This pump should 45 be located at a sufficient distance below the surface of the ground to receive the water before its pressure has been reduced sufficiently to permit vaporization and cooling 50 thereby. The pump may be located for example from 60 to 100 feet below the surface of the ground, or it may be located at even a lower level if desired.

The water pumped from the ground 55 passes through the pipe 13 to the heater 12. On its way it may be purified in the purifier 18 or filtered in the filter 19, or both purified and filtered, before it reaches the heater 12. The purifier may contain lime or other 60 chemicals for neutralizing the acid or corrosive chemicals contained in the water and the filter may remove any matter thus precipitated as well as any matter carried mechanically in the water, or the filter may be

of a selective character which will absorb 65 oil or other impurities from the water.

From the heater 12 the hot water is conveyed by the pipe 16 to the pump 17 by which it is again pumped to the well 1.

In the heater 12 the mine water may be 70 heated either by high pressure steam from the power plant introduced through the line 15, or by admixture with hotter superheated water from the power plant introduced through the line 14, or by a combination of 75 both of these heating means, as above described. The heated water can be used alone or it can be admixed with additional fresh hot water entering the well through the line 4. 80

At the beginning of the mining operations of the dome, the sulphur wells are advantageously located near the top of the dome near the location of the well 6 and such wells are operated until the sulphur is exhausted 85 at that location or until subsidence of the ground causes breaking of the piping equipment. As the ground surrounding the first wells becomes exhausted, additional wells are drilled at a distance from the first wells. 90

These wells may be at a location such as illustrated by the well 1 in the drawing and the well 6 may be an exhausted well which is used merely for the purpose of withdrawing 95 the hot water from the upper part of the deposit. The upper part of the deposit forms a heat reservoir where the hottest water tends to accumulate in a portion of the deposit from which the sulphur has been exhausted and in the porous cap rock where 100 it serves no useful purpose in melting sulphur and where it causes great heat loss and low heat efficiency. In the process of the present invention, the relatively pure hot water is withdrawn from this hot zone 105 where it is hottest and where the hot water is kept localized and the hot water thus withdrawn is kept under pressure so as to maintain its temperature and it is then reheated and reutilized in the manner above 110 described. The temperature of the water thus withdrawn may be as low as 200° F., or even lower, but after the mining operation has continued for sometime, the water 115 will be at a much higher temperature, as high as 260° F. or even higher. By withdrawing water at this temperature and admixing it with water heated to a much higher temperature e. g. around 365° F., the mixture can be so regulated in proportion of 120 the mine water and much hotter water to get a composite product of the proper temperature for reintroduction into the mine e. g. at around 320 to 324° F. It will be 125 evident that the relative amounts of mine water and of fresh hot water will vary with the temperature at which the mine water is withdrawn as well as with the temperature

at which the hot water is supplied from the power plant.

To the extent that the hot mine water is withdrawn and reutilized, the heat necessary to heat up a corresponding amount of fresh water to the same temperature is saved. Instead of supplying 256 B. t. u.'s per pound of water heated from 68° F. to 324° F., only 64 B. t. u.'s are required to heat a pound of mine water from 260° F. to 324° F. The large economies which such reutilization of the hot mine water makes possible will be appreciated if we take an example where the fresh water is supplied to the power plant at a temperature of 68° F. and where the average temperature of the water supplied to the wells is 324° F. The heat required to heat one pound of water from 68 to 324° F. is 256 B. t. u.'s. If however a smaller amount of water is heated to a much higher temperature, e. g. 364° F., the amount of heat is only 296 B. t. u.'s or 40 B. t. u.'s more than for heating the same amount of water to 324° F. But by mixing one and one-half pounds of water heated to 364° F. with one pound of mine water which is at a temperature of 260° F., and allowing a loss of 4 degrees between the plant and the point of mixing and final temperature at the wells, there is attained two and one-half pounds of well water at 320° F. Accordingly, instead of heating two and one-half pounds of water from 68° F. to 324° F., it is only necessary to heat one and one-half pounds from 68 up to 364° F., and to admix the latter amount with one pound of mine water at 260° F., to obtain a similar amount of water at the desired temperature of 320° F. Calculating this economy in terms of increased production of sulphur per pound of fuel oil used in the power plant, the economy or increased production amounts to around 44 percent where the mine water is withdrawn at a temperature of 260° F. With mine water withdrawn at 250° F., the economy is 35.8 percent increased production per pound of fuel oil. At 240° F. temperature of the mine water withdrawn, the increased production is about 29.7%. Even with the temperature of the mine water at 200° F., an increased production of sulphur of about 15.2 percent is obtained. This economy is obtained by using the heat already contained in the mine water, and by making this hot water which is already preheated serve as a carrier for the additional heat units without raising the final temperature above the point at which the sulphur becomes viscous.

Instead of supplying all of the heat to the water which is withdrawn from the mine in the form of superheated fresh water, a part of the heat may be supplied in the form of high pressure steam from the power plant. By regulating the amount of fresh

hot water introduced and supplying a regulated amount of additional heat by superheated steam, the amount of fresh hot water added to the deposit can be regulated and controlled. In this way the supply of fresh water in the deposit can be gradually increased to allow of the removal of the original and foul deposit water and its eventual replacement by fresh water; but this replacement by fresh water is not effected rapidly as in present operations where all of the hot water pumped into the mine is permitted to accumulate and to displace the mine water downwardly at a relatively rapid rate.

Eventually, as the mine is worked to progressively lower levels, and as the mine water tends to be more or less completely removed and replaced by fresh water so that the mine becomes full or approximately full of heated water, an increased amount of the heat can be supplied in the form of steam and an increased amount of the hot water can be withdrawn and purified and returned for the continuation of the mining operation.

It will be evident that suitable thermometers and regulating valves as well as thermostatic controlling devices can be provided for regulating the mixing of the water from the plant with the hot water from the mine so as to obtain a mixture for delivery to the well at the proper temperature.

The present invention enables a simplification to be obtained in the power plant which supplies hot water, or superheated steam for the mining operation. In such power plants, as now operated, high pressure steam is generated in boilers and is admixed with water in mixers operating on the jet condenser principle and the water is thus heated to the proper temperature for the mining operation. The feed water for the boilers or for the heaters or both may be preheated by the exhaust steam from the power plant. The same power plant can be used in carrying out the process of the present invention, but with the utilization of a decreased amount of steam. There should be a sufficient amount of steam for reheating the mine water, or steam at a higher temperature and pressure to heat the fresh water to the necessary higher temperature for admixture with the hot mine water.

As considerable power will be used at all times for pumping, compressing air, lighting, heating and general distribution of electrical power around the mine, there will always be heat available from the source of the various engines which can be used to advantage in preheating the fresh water from the reservoir to say 200° F. so that a certain amount of fresh water is always available in excess of the boiler feed water without loss of efficiency, until such time as the

amount of hot water accumulated in the mine has increased in amount and has become sufficiently clean for reuse and sufficiently high in temperature to equal the temperatures and volumes at which water might be discharged from condensers. At such time, the use of steam in the power plant may be cut down to a minimum by the use of highly efficient steam or other engines, and the heat from the exhaust may be wasted, except to the extent that it may be used for the preheating of such feed water as is still supplied to the power plant and mining operation. At such time as the mine becomes practically filled with hot and clean water, a minimum of fresh hot water can be supplied for the mining operation and the greater part of the mining operation can be carried out by recirculation of the mine water, with purification and reheating thereof by the use of steam as above described.

The improved process of the present invention presents the advantage, among others, that the application of highly heated water to the dome is localized. The hot water introduced at the mine where the active mining operation is going on tends to rise and flow towards the top of the dome. By withdrawing the hot water from near the top of the dome, the tendency is for the hottest water introduced at the mine to flow in the direction of the wells through which the hot water is withdrawn. The hottest water thus tends to stay in the upper layer of water in the dome and to be replenished by the fresh hot water flowing from the active wells. In this way, the hottest water is kept away from the sulphur bed remote from the active wells and remote from the top of the dome and only the cooler water at the lower levels comes in contact with such remote portions of the bed. This withdrawal of hot water from the top of the dome keeps down the accumulation of hot water in the dome and reduces the total volume of new hot water introduced and accumulated in the deposit and so tends to prevent the overheating of the deposit and discoloration of sulphur before its extraction by delaying the advance downward of the heated zone. This heated zone, as above described, can be regulated in its downward advance by regulating the amount of fresh hot water admixed with the hot water withdrawn from the mine and reheated and reintroduced therein. The loss of sulphur around the bottom of the edges of the deposit through premature melting before it can be extracted is also reduced or minimized.

It will thus be seen that the present invention involves an important economy of operations both in the amount of heat required for conducting the mining operation and in the heat which would otherwise be lost or which might even be objectionable

and injurious if permitted to accumulate and increase in the deposit. It will further be seen that the hot water is withdrawn at a considerable distance from the well where it is introduced but nevertheless at the point where the water of approximately maximum temperature is to be found in a deposit. It will also be noted that the bleed wells are located at a still lower level or at a further removed point of the deposit where the water withdrawn therethrough will be the cold salt water or the cooler water from the lower levels of the deposit.

In the mining of sulphur by drilling successive wells to the underlying sulphur strata of the dome, the mining can advantageously be carried out by begining near the center or top of the dome and working outwardly from the center and progressively exhausting the sulphur from areas more and more remote from the center and from the top of the dome. When the wells reach a point which is distant from the center, and particularly a point which is at a lower level, the hot water will then tend to accumulate at the still higher levels near the top of the dome from which the sulphur has already been exhausted. This is advantageous in the process of the present invention; and the progressive mining of the dome can be carried out in the manner above described and with reutilization of the accumulated hot water in the mine in such a way to obtain important heat economies, as well as to obtain advantages in the operation of the mine itself, and the avoidance of objectionable over-heating at points remote from the exhausted and active mining zones.

It will further be seen that in the process of the present invention, the difficulties arising from the use of the mine water are overcome and its corrosive and scale forming properties are neutralized by suitable treatment, and objectionable amounts of oil carried thereby are removed so as to avoid contamination of the sulphur therewith; and fresh water is introduced in admixture therewith to insure the gradual heating of the deposit down to the level at which sulphur is being extracted so that ultimately extraction of sulphur from the bottom or foot wall of the deposit is assured. It will further be seen that a sufficient amount of fresh water is introduced to insure the removal of the original foul deposit water through the bleed wells so as to avoid admixing of this water with the hot water which is withdrawn and reutilized.

As an apparatus or system, it will be seen that the invention provides for one or more wells extending to the top of the deposit where the reservoir of hot water has accumulated together with means for pumping this hot water from the deposit and maintaining it under pressure and for reheating

it and reintroducing it into the active well; together with oil filters or separators for removing oil from the water should any be present; and purifiers, filters, settlers, etc., for the separation of scale or corrosive constituents so that the water will not corrode or scale the well pipes to any considerable extent. The system or apparatus also includes a heater for heating the water so withdrawn, either by high pressure steam from the power plant, or by highly superheated water, and for regulating the temperature of the reheated water and the mixing of the fresh water therewith for delivery to the wells at the proper temperature. It will further be seen that the system includes one or more wells at a point remote from the top of the dome in combination with a well for withdrawing hot water from the top of the dome so as to obtain a general direction of flow of hot water in the deposit from the active wells to the top of the dome from which the hot water is withdrawn; while the cold water is withdrawn from the deposit by bleed wells extending to a lower level.

The system or apparatus of the present invention also enables an economy in power plant operation to be obtained since by operating the power plant at a higher steam pressure the amount of water which it is necessary to heat can be greatly reduced. The reduction in cost of operation of the power plant, and the great reduction in amount of fuel required for heating water, involves large savings in operation while at the same time enabling the mining of the sulphur in the dome to be better regulated and controlled.

40 I claim:—

1. The improvement in the mining of sulphur by underground fusion from partially exhausted sulphur deposits, which comprises withdrawing from the upper part of the deposit hot water, at a temperature slightly below or higher than the melting point of sulphur, which water has preferentially accumulated in the upper part of the deposit, reheating the water withdrawn, reintroducing the reheated water into the deposit, admixing additional fresh superheated fluid therewith before introduction, and withdrawing cold water, at a temperature well below the melting point of sulphur, from 55 the mine.

2. The improvement in the mining of sulphur by underground fusion from partially exhausted sulphur deposits which comprises withdrawing part of the hottest water from the exhausted upper part of the deposit, reheating the water so withdrawn, and reintroducing the reheated water at a localized well zone remote from the point of withdrawal.

65 3. The improvement in the mining of sul-

phur by underground fusion from partially exhausted sulphur deposits, which comprises conducting superheated water into the formation containing the sulphur and thereby melting the sulphur, continuing such introduction of superheated water and simultaneously withdrawing relatively cold water from a lower level of the deposit until a preferential accumulation of hot water occurs in the upper part of the deposit, and thereafter regulating the further accumulation of such hot water in the deposit by withdrawing a part of the accumulated hot water, at a temperature slightly below or higher than the melting point of sulphur, reheating the hot water withdrawn and admixing therewith a regulated amount of fresh superheated fluid, reintroducing the resulting admixture into the deposit, and continuing to withdraw a regulated amount of cold water, at a temperature well below the melting point of sulphur, from a lower level of the deposit.

4. The improvement in the mining of sulphur by underground fusion from partially exhausted sulphur deposits which comprises withdrawing a part of the hot water from near the top of the deposit, reheating the water withdrawn and admixing therewith a regulated amount of fresh superheated water, reintroducing the resulting superheated water into the deposit at a well zone remote from the point of withdrawal of the hot water, and regulating the further accumulation of hot water in the deposit by regulating the amount of fresh superheated water admixed with the reheated water from the deposit and by a regulated withdrawal of cold water from a lower level of the deposit.

5. The improvement in the mining of sulphur by underground fusion from partially exhausted sulphur deposits, which comprises withdrawing superheated water from the upper part of such deposit while such water is superheated above 212° F., maintaining such superheated water under pressure to prevent vaporization and cooling thereof, reheating said water and reintroducing the same into the deposit at a well zone remote from the point of withdrawal, and regulating the accumulation of hot water in the deposit by introducing additional superheated fluid into the deposit and separately withdrawing a regulated amount of cold water, at a temperature well below the melting point of sulphur, from the deposit.

6. The improvement in the mining of sulphur by underground fusion from partially exhausted sulphur deposits which comprises withdrawing superheated water at a temperature higher than 212° F. from the deposit by means of a pump located a sufficient distance below the surface of the ground to maintain the water withdrawn under pressure and prevent vaporization

thereof, pumping the water so withdrawn through a heater and thereby reheating the same under pressure, and reintroducing the reheated water into the deposit at a well zone remote from the point of withdrawal.

7. The improvement in the mining of sulphur by underground fusion from a sulphur deposit containing an accumulation of hot water in the exhausted upper portion of the deposit which comprises withdrawing sulphur from the deposit, independently withdrawing hot water at a temperature slightly below or higher than the melting point of sulphur from such accumulation, reheating the same by admixture therewith of fluid superheated to a much higher temperature, and reintroducing the reheated water into the deposit.

8. The improvement in the mining of sulphur by underground fusion from a sulphur deposit containing an accumulation of hot water in the exhausted upper portion of the deposit which comprises withdrawing hot water at a temperature slightly below or higher than the melting point of sulphur from 'said accumulation, maintaining the withdrawn water under pressure to prevent vaporization, reheating the withdrawn water by admixture with fresh fluid superheated to a much higher temperature, reintroducing the reheated water into the deposit at a mine zone remote from the point of withdrawal, and independently withdrawing cold water at a temperature well below the melting point of sulphur from a lower level of the deposit.

9. The improvement in the mining of sulphur by under ground fusion from partially exhausted sulphur deposits which comprises withdrawing sulphur from the deposit, independently withdrawing hot water from the upper part of the deposit at a temperature between 200 and 260° F., reheating the water so withdrawn by admixture with fresh fluid superheated to a much higher temperature to give a resulting mixture of a temperature around 320 to 324° F., and reintroducing the reheated water and admixed fresh fluid to the deposit.

10. The improvement in the mining of sulphur by underground fusion from partially exhausted sulphur deposits which comprises withdrawing hot water at a temperature slightly below or higher than the melting point of sulphur from the upper part of the deposit, reheating the water withdrawn, reintroducing the reheated water into the deposit at a well zone remote from the point of withdrawal, introducing additional superheated water into the deposit at the well zone, independently withdrawing cold water at a temperature well below the melting point of sulphur from a lower level of the deposit and subjecting the hot water so withdrawn and reheated to purification for the

separation of oil therefrom before its reintroduction into the deposit.

11. The improvement in the mining of sulphur by underground fusion which comprises withdrawing hot water at a temperature slightly below or higher than the melting point of sulphur from the upper part of the deposit, reheating the water withdrawn in part by steam under pressure and in part by admixture with fresh superheated water at a higher temperature, and reintroducing the reheated water into the deposit at a mine zone remote from the point of withdrawal.

12. The improvement in the mining of sulphur by underground fusion from partially exhausted sulphur deposits, which comprises withdrawing hot water, at a temperature slightly below or higher than the melting point of sulphur, from near the top of the deposit, purifying the water to free it from corrosive and scale-forming constituents, reheating the water by superheated fluid, separately withdrawing cold water at a temperature well below the melting point of sulphur from a lower level of the deposit, and regulating the accumulation of hot water in the deposit by regulating the amount of fresh superheated fluid admixed with the withdrawn water and the amount of cold water withdrawn to obtain a heated zone gradually and progressively extending downward in the deposit.

13. In the mining of sulphur by underground fusion from partially exhausted sulphur deposits, one or more wells arranged to permit withdrawal of hot water at a temperature slightly below or higher than the melting point of sulphur from near the top of the deposit, one or more wells arranged for conducting superheated water into the sulphur-containing formation at a distance from the wells first mentioned, means for pumping hot water at a temperature slightly below or higher than the melting point of sulphur from the top of the deposit to the surface of the ground through said first mentioned wells and for maintaining such water under pressure, one or more reheaters for reheating the water so withdrawn, said reheaters being supplied with a heating medium from a power plant located at a distance therefrom, and means for reintroducing the reheated water into the sulphur-mining well or wells as the heating medium therefor.

14. In the mining of sulphur one or more wells extending to the sulphur-containing deposit for introducing superheated water into the deposit and for removing molten sulphur therefrom, one or more wells extending to the upper part of the deposit from which the sulphur has been exhausted, pumps in said last mentioned wells for pumping the hot water at a temperature slightly below or higher than the melting

point of sulphur from the upper part of the deposit and maintaining it under pressure, means for purifying the water so withdrawn from the deposit, means for admixing with the water so withdrawn fresh superheated fluid, and means for introducing the resulting water into said first mentioned wells.

15. In the mining of sulphur one or more wells extending to the sulphur-containing deposit for introducing superheated water into the deposit and for removing molten sulphur therefrom, one or more wells extending to the upper part of the deposit from which the sulphur has been exhausted, 15 pumps in said last mentioned wells for pumping the hot water at a temperature slightly below or higher than the melting point of sulphur from the upper part of the deposit and maintaining it under pressure, 20 means for reheating the water by admixture therewith of fresh superheated fluid

from the power plant, means for returning the resulting water to said first mentioned wells, and means for withdrawing cold water at a temperature well below the melting point of sulphur from a lower level of the deposit.

16. The improvement in the mining of sulphur by underground fusion from partially exhausted sulphur deposits, which comprises withdrawing hot water from the upper part of the deposit, at a temperature slightly below or higher than the melting point of sulphur, which water has preferentially accumulated in the upper part of the deposit, reheating the water withdrawn, admixing additional fresh superheated fluid therewith, and reintroducing the reheated water into the deposit.

In testimony whereof I affix my signature.

ROBERT HOLDEN STEWART.

point of sulphur from the upper part of the deposit and maintaining it under pressure, means for purifying the water so withdrawn from the deposit, means for admixing with the water so withdrawn fresh superheated fluid, and means for introducing the resulting water into said first mentioned wells.

15. In the mining of sulphur one or more wells extending to the sulphur-containing deposit for introducing superheated water into the deposit and for removing molten sulphur therefrom, one or more wells extending to the upper part of the deposit from which the sulphur has been exhausted, 15 pumps in said last mentioned wells for pumping the hot water at a temperature slightly below or higher than the melting point of sulphur from the upper part of the deposit and maintaining it under pressure, 20 means for reheating the water by admixture therewith of fresh superheated fluid.
